UNITED STATES PATENT OFFICE.

DANIEL J. WULFING, OF ST. PAUL, MINNESOTA, ASSIGNOR TO THE MINNESOTA SPECIALTY COMPANY, OF ST. PAUL, MINNESOTA, A CORPORATION OF MINNESOTA.

AUTO KEY CASE.

Application filed June 3, 1925. Serial No. 34,608.

My invention relates to an auto key case in which it is designed to provide a key case particularly adapted for holding an auto key or several keys in a small compact state so that the keys are readily accessible and form a firm package when they are attached on the instrument board of an automobile.

A feature of my invention resides in presenting a key case made of a small single piece of leather folded over and stitched at one end to form an inclosure at that end and to provide an open end opposite the stitching which is adapted to carry a snap catch so that the open end of the case can be snapped and locked together to hold keys in the case.

It is also a feature of my invention to provide a snap catch for holding the keys having a shank a little longer than is ordinarily provided for such snaps which forms a rod extending between the sides of the key case when the snap catch is closed on which the keys are pivotally carried. The shank is securely fastened to one side of the key case at the open end thereof, and can be provided to carry a single washer or several washers to form spacers between the sides of the key case. The spacers carried by the snap catch shank are only for the purpose of providing a snug fitting between the key and the key case, and to prevent too free connection, so that the key held in the case would rotate too freely on the back. It is desirable to have the key fit quite snugly in the case.

An object of my invention resides in a key case adapted to holding an auto key so that when the key is inserted in the instrument board, the key case will project from the key rather than hang down against the instrument board and thus prevent scratching of the instrument board of the automobile.

This feature of holding the case extending straight out from the key when the key is in use is also quite an advantage, as it permits the user of the case to readily apprehend just the position of the key, so as to known how to insert the same into the lock of the instrument board, even in the dark. When the key is not desired for use it can be folded over into the key case where it is practically completely concealed and protected by the sides of the case. The key is

pivots held in knife-blade like position in my key case, this is a feature of the invention.

The simplicity of my key case is part of my invention as a case for a small number of keys which can be used for any purpose, making a desirable key case for a lady which can be readily carried in her purse or otherwise, and in providing a key case wherein the keys held therein can be so positioned that the user of the key case knows just whether the key is right side up to be inserted into the lock for which it is designed.

These features together with other details of the construction will be more fully set forth in the following specifications and claims.

In the drawings forming part of this specification;

Figure 1 illustrates my key case in operation and diagrammatically illustrates a portion of an instrument board of an automobile.

Figure 2 illustrates the side view of my key case as it would appear in use.

Figure 3 is a perspective view of my key case.

Figure 4 is a plan view of my case showing the key folded into the same.

Figure 5 is a view illustrating the died out formation of the body or leather part of my key case.

Figure 6 illustrates one of the spacing washers.

Figure 7 illustrates the rivet head and shank of the snap catch.

Figure 8 illustrates the button of the snap catch.

In the drawings my key case A is formed of a single piece of leather 10 or other suitable material of a flexible nature which forms the body of the key case. In the flat formation of the body of the key case A leather 10 is died out in the formation illustrated in Figure 5 of the drawings. Obviously this formation can be of a suitable nature but it is desirable to have it so shaped as to form a practically rectangular book like compartment when the body portion 10 is folded.

The body portion 10 is divided into two equal half portions 11 and 12 which are at

tached to form the side walls of the key case A when the same is folded along the line 13. In folding the body 10 to form the sides 11 and 12, the key case A is formed with a key compartment B into which the keys are adapted to rest when they are not desired for use.

After the body portion 10 is folded along the line 13, the one end of the key case A 10 is stitched at 14 so as to close the end of the case and the stitching forms means to hold the sides 11 and 12 against each other at the closed end of the key case.

At the other end of the key case, which 15 constitutes the open end so as to speak, I provide a snap catch C which is formed with the rivet head 15. This rivet head 15 is provided with a long shank 16 which carries the grooved locking head 17.

20 The drawings illustrate the rivet head 15 attached to the side 12 in Figure 3, while the side 11 of the case A carries the button or female portion 18 of the snap catch C. The shank 16 of the rivet head 15 may be 25 of any suitable length so as to space the sides 11 and 12 apart at the free or open end of the key case A in a manner so that the shank 16 provides a pin for carrying the keys such as E pivotally supported by the 30 sides 11 and 12 in a knife-blade like manner as illustrated in the drawings.

Where only one or two keys are used in the case A I prefer to use a spacing washer such as 19 which are formed of leather or 35 other suitable material and which are comparatively thick, so as to form the desired spacing means between the key and the body or walls 11 and 12.

40 The keys E are placed on the shank 16 and the snap catch C is closed so as to lock the sides 11 and 12 together to hold the keys between the side so that they can be turned out as illustrated in Figure 2 for use, or folded back into the case between the side 45 walls 11 and 12 as illustrated in Figure 4. The small neat compact formation of my key case is desirable for small number of keys and more particularly for an automobile key or keys so that the keys can be readily accessible, and when in use the key case A is 50 adapted to project straight out from the key and form a handle engaging means as illustrated in Figure 1, where the key case A is used to indicate the key E inserted in an 55 instrument board F of an automobile. The instrument board is only illustrated diagrammatically as this is of well known ordinary construction.

60 The simple inexpensive construction of my key case is a very important part of the invention as it permits me to make a small compact key case with a single piece of leather or other flexible material, which is

folded in book-leaf form to provide side walls between which the keys are held. The 65 knife blade like hinging of the keys to the snap catch at the open end of the key case permits keys to be quickly inserted or detached from the case, and in this manner a 70 very simple effective key case is provided. 75

It is important in my invention that the key case A be held to project outward from the keys held therein when the key is in use to form a gripping or handle means and to hold the key, particularly when it is used 80 in connection with an auto instrument board with the key case extending straight out from the key, and to permit the distinguishing of the position of the key in the case, so that it can be readily inserted into the lock 85 of the instrument board.

90 A reason why my key case is important, which is now so apparent, is that the general use of automobiles today and the necessity of locking the same to prevent thefts or disturbances when the owner is not in the auto, has established a demand for a key case of this nature. My key case fulfills this desire of the automobile owner in providing 95 a key case of simple inexpensive construction which effectively covers the keys or key held therein, and keeps the automobile key separate from the other keys so that they are readily accessible for use.

100 In accordance with the patent statutes, I have described the principles of operation of my invention, and while I have illustrated a particular formation of my key case in the drawings, I desire to have it understood that these are only illustrations and that the invention can be carried out by other means and applied to uses other than those above set forth within the scope of the following 105 claims.

I claim:

110 1. A key case for automobile keys including, a cover formed from a single piece of flexible material, said cover being folded centrally to provide side walls of a rectangular shape, stitching along one end of said cover to close the end of said key case, and snap catch locking means attaching to the other end of said key case adapted to provide means for holding keys by said snap catch for the purposes specified. 115

120 2. A compact key case having small dimensions including a cover formed of a single piece of leather folded in a manner to provide a longitudinally extending key receiving compartment, means for entirely closing one end of said compartment, and means for detachably holding keys in the other end of said compartment, adapted to pivot in knife-blade like connection between the sides of said cover. 125

DANIEL J. WULFING.
